The ornamental design for a keyboard, as shown and described.

DESCRIPTION

FIG. 1 is a perspective view of a keyboard, showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a top-front perspective view of a keyboard of FIG. 1, in which a docking part of the keyboard rotates on a hinge; FIG. 9 is a top-right perspective view of a keyboard of FIG. 1, in which a docking part of the keyboard rotates on a hinge, and a mobile terminal in broken lines docks with the docking part of the keyboard to illustrate an example environment; FIG. 10 is a top-right perspective view of a keyboard of FIG. 1, in which a mobile terminal in broken lines docks with a docking part of the keyboard and folds with the keyboard to illustrate an example environment;

FIG. 11 is another top-right perspective view of a keyboard of FIG. 1, in which a docking part of the keyboard rotates on a hinge; and,

FIG. 12 is a partially enlarged top view of the portion, a-a', b-b', c-c', and d-d', in FIG. 11.
The broken lines in the drawings illustrate portions of a Keyboard which form no part of the claimed design. The shaded lines in the figures show contour and not surface ornamentation.

The dot-dot-dash broken lines identifying a-a', b-b', c-c', and d-d' of the claimed design that are illustrated in an enlargement form no part of the claimed design.
